UNITED STATES PATENT OFFICE.

JOHN F. GRACE, OF KEARNY, NEW JERSEY, ASSIGNOR TO WORTHINGTON PUMP AND MACHINERY CORPORATION, A CORPORATION OF VIRGINIA.

CONDENSER SUPPORT.

Application filed July 8, 1920. Serial No. 394,762

To all whom it may concern:

Be it known that I, JOHN F. GRACE, a citizen of the United States, residing at Kearny, county of Hudson, and State of New Jersey, have invented certain new and useful Improvements in Condenser Supports, fully described and represented in the following specification and the accompanying drawings, forming a part of the same.

10 This invention relates to improvements in means for supporting condensers, and particularly to means for supporting condensers used with turbine engines.

A condenser is subjected to several forces which are of considerable magnitude and some of which vary according to operating conditions. Among the most important of these forces are the weight of the condenser and its attached parts, the weight of the 20 water and vapor in the condenser, the thrust due to the reaction of the atmosphere on the condenser, and the force due to expansion and contraction of the condenser.

The force due to the condenser dead weight, that is to say the weight of the empty condenser with any attached parts it may carry, of course, tends to produce a displacement or movement of the condenser in a downward direction and is always constant for any given condenser.

The force due to the weight of the water and vapor in the condenser acts in a downward direction, but may vary considerably from time to time.

35 The force due to the atmospheric reaction will have its direction determined by the direction of exhaust discharge but in the present general practice the exhaust is discharged downward so that the reactive force on the condenser may be in an upward direction. This is balanced by the downward pressure on the turbine if a rigid exhaust connection be used, but not with an expansion joint in the exhaust connection.

45 Considering now the effect of these three forces, it will be obvious that when for any reason there is no water in the condenser, the latter is subjected only to a downward pull equal to its dead weight. Under normal operating conditions the condenser is subjected to a downward force which is the sum of the condenser dead weight and the weight of the water it contains, and if the

engine is running, the condenser is subjected to a force which is the resultant of the three forces, viz.—reactive thrust upward, condenser dead weight downward and weight of water and vapor downward. In practice this resultant force acts downward. That is, the exhaust reaction is less than the total weight of the condenser and of the water and vapor.

Because of the stress due to expansion and contraction of the condenser, the condenser support must be such that this expansion and contraction may take place without injury to the condenser or the engine with which it is connected.

Many attempts have been made heretofore to provide a condenser support which will satisfactorily meet the conditions of practice, but prior to this invention no support has been devised on such a principle that it would satisfactorily take care of all the conditions arising in practice.

The present invention overcomes all the disadvantages of the prior constructions by supporting the condenser in such a manner below the turbine that the condenser may expand freely downward while at the same time the constant downward pull on the condenser due to gravity is counterbalanced by a substantially equal constant upward thrust and the varying resultant of the other varying forces is transmitted to the foundation of the turbine or other engine in a suitable way as, for example, through the turbine casing or base.

By this invention, the expansion of the condenser, which sometimes is brought about by accidental stoppage of the circulating pump and the resultant heating of the condenser, cannot cause an upward thrust on the turbine and hence there is no danger of forcing the turbine rotor or shaft out of alignment by this accidental stoppage.

If for any reason the flow of water stops and the condenser empties, the turbine is relieved of any upward thrust due to the exhaust by the immediate opening of the free exhaust valve always provided in such installations.

A further great advantage of this arrangement is that the engine casing is readily freed of all load due to the condenser

merely by drawing off the water from the condenser. This is particularly important on account of the necessity of opening the engine casing at times to obtain access to the engine for inspection and repairs. At such times, the engine casing is in no condition to resist any stresses from the condenser, and it is usual to line up the turbine shaft with the weight of the condenser taken off the turbine. In one type of condenser support heretofore employed it has been customary to connect the condenser directly to the exhaust of the turbine and then support the condenser yieldingly on springs; but in such constructions it has been considered necessary to so construct and adjust the springs that they carried only a part of the weight of the condenser, while the exhaust flange of the turbine carried the remainder of such weight as well as the weight of the water. Otherwise with the condenser relieved of the weight of the water, either wholly or in part the springs produced an upward thrust on the turbine exhaust flange which was very disadvantageous as liable to put the rotor or shaft out of alignment.

While in its broad aspect the invention is not limited to the specific means employed for maintaining constantly a uniform upward thrust on the condenser substantially equal to condenser dead weight, I have devised some special types of mechanism which will insure this uniformity of thrust under all conditions of practice. In these new types gravity is relied upon as the balancing force to counterbalance the condenser dead weight, and the mechanism is such as not to be injuriously affected by operating conditions.

Notwithstanding the fact that the mechanisms devised by me are peculiarly adapted for counterbalancing the condenser dead weight, as hereinbefore explained, it is to be understood that they can be used to give an upward thrust either less than or more than equivalent to the condenser dead weight, if circumstances arise which make this advisable or desirable.

An important further advantage of these new supporting mechanisms is that they can be arranged to give a symmetrical distribution of the stresses on the engine exhaust conduit, so that the resultant stress may be uniformly distributed on the flange of said conduit.

One type of such new mechanism comprises hydraulic means for applying the counterbalancing thrust, while another type comprises ordinary weights arranged to counterbalance the weight of the condenser.

Although the hydraulic counterbalancing means is embraced within the broad scope of the invention, no specific claims are made to it in the present application, but such

claims are presented in the companion application filed July 8, 1920, Serial No. 394,761.

The invention will be more specifically described herein in connection with the accompanying drawings, in which—

Figure 1 shows a side elevation of a turbine installation, the condenser being supported by the preferred embodiment of my invention;

Figure 2 shows a top plan view;

Figures 3 and 4 are detail elevations;

Figure 5 shows a top plan view of a modification;

Figures 6 and 7 show elevations thereof, and

Figure 8 is a side elevation of a modification of the invention showing a turbine installation including a condenser and one form of hydraulic mechanism for supporting the condenser.

Referring to the drawings, the turbine installation shown by the way of example is of the common form in which the turbine is provided with a bottom exhaust conduit 90 having a flange 10 to which is connected directly the top exhaust inlet 11 of a suitable surface condenser B, provided with columns or legs 12, in the present example four in number, as shown and having suitable knife edges 1.

In the specific embodiment of the invention shown in the drawings there is provided a suitable lever and weight support which advantageously is of the form shown in Figs. 1, 2, 3 and 4 of the drawings, in which each of the knife edges 1 of the columns or legs 12 bears on a multiplying lever 13, fulcrumed at its outer end on knife edge 2 resting on a fulcrumed support, such as, for example, the column 14. The inner ends of the levers 13 bear on a common central bearing plate 15. A balancing lever 16 supported on knife edge 3 by a fulcrum support, such as a short column 17, engages at its inner end the knife edge 4 of the common central bearing plate 15 and carries at its outer end an adjustable balancing weight 18 which may be secured in any adjusted position by a suitable device such as a screw 19. Multiplying levers 13 are preferably provided with adjustable bearing screws 20 bearing against the bearing plate 15 for leveling and final balancing of the condenser.

Suitable small bearing plates 5 are preferably provided on the columns and levers for the knife edges.

The columns 14 and 17 are preferably of the form shown in which each consists of two supporting members *a*, one on either side of the lever to be supported, secured or cast integrally with common base *b*.

The operation of the support is as follows: The condenser is levelled and accurately

balanced, when empty, by adjustment of weight 18 and bearing screws 20, so as to bring the flanges of the turbine exhaust and condenser exhaust inlet into close contact. 5 The turbine exhaust flange 10 and the top exhaust inlet 11 of the condenser are then securely locked together as, for example, by bolts 21. When the circulating pump and turbine are started, the condenser fills 10 with water and steam, the weight of which is carried by the turbine exhaust flange 10 as well as the thrust produced by the reaction of the exhaust. Since these forces are 15 in opposition to each other, the exhaust flange 10 is subjected only to the resultant force.

Figures 5, 6 and 7 show a modification which differs only in that it is provided with two long and two short multiplying levers, 20 respectively, as indicated at 21 and 22, these levers being each fulcrumed at one end on columns 23. On these levers rest the feet of the condenser columns 12, the inner ends of the levers 22 being provided with bearing screws 24 which bear upon the levers 21. The free ends of the levers 21 pass through the lower eyes of two double eye-members 25 which are supported on a balance lever 26 by knife edged bar 27 which 30 passes through the two upper eyes. The balance lever 26 is fulcrumed on a suitable fulcrum support as, for example, the column 28, Fig. 7, and is provided with the adjustable weight 29, which may be secured by a screw 30.

It is desirable that the counterweight should be as near the floor as possible in order to prevent any accidental throwing of a further weight thereon producing an upward thrust. This is not absolutely necessary, however, as the base of the condenser and its supporting means may be enclosed after the adjustment has been made.

Referring to Fig. 8 of the drawings, the 45 turbine installation shown by way of example is of the common form, in which the turbine is provided with a bottom exhaust conduit having a flange 110 which is connected directly to the top exhaust 111 of a suitable condenser B', preferably of the surface type, having a hot well 112 projecting centrally from its bottom.

In the form of this invention shown in 50 Fig. 8, the hot well 112 is provided with a large plunger 113 operating within a cylinder 114, embedded within the engine room floor. To the cylinder 114 and below the piston 113 fluid under pressure is delivered by suitable means, which may be 55 of the form shown, in which static tank 115, provided with suitable overflow and float-controlled leakage make up connections 116 and 117, respectively, delivers the pressure fluid through a connection 119.

Since it will be impossible to obtain the

same static heights in all engine rooms, it is preferable, therefore, to form the plunger 113 for such static height as may be obtainable in each instance. Wherefore, the operation consists in so proportioning the 70 height of the static tank and the size of the plunger 113 that the fluid under pressure shall accurately support the condenser dead weight, that is, the weight of the empty condenser and any attached parts. The turbine exhaust flange 110 and the top exhaust inlet 111 of the condenser are then secured together, as by bolts, the weight of the water and steam within the condenser being carried by the exhaust flange 110 of the turbine A'. 75 Also, the thrust due to the reaction of the exhaust is transmitted to the engine through the exhaust flange, but as this reaction is in opposition to the action of the weight of water and vapor, the exhaust flange is 80 subject only to the resultant.

It will readily be appreciated that any changes in vertical height of the condenser due to expansion and contraction will be compensated for by a corresponding movement of the counterweight while at the same time the condenser deadweight is always counterbalanced properly.

What is claimed is:

1. The combination, with an engine, its 95 supports, and a condenser below the engine and arranged to receive exhaust steam therefrom, of yielding means for constantly maintaining a uniform upward thrust upon the condenser substantially equal to the condenser dead weight, and means for transmitting to the engine supports the resultant of all displacement forces acting upon the condenser other than that due to the said condenser dead weight.

2. The combination, with an engine, its 100 supports, and a condenser below the engine and arranged to receive exhaust steam therefrom, of movable bearing means for carrying the condenser, means for applying a 105 gravitational force to said bearing means in opposition to and substantially equal to the condenser dead weight, and means for transmitting to the engine supports the resultant of all displacement forces acting upon the condenser other than that due to said condenser dead weight.

3. The combination, with an engine, its 110 supports, and a condenser below the engine and arranged to receive exhaust steam therefrom, of movable bearing means for carrying the condenser, weighted mechanism arranged to transmit to said bearing means an upward thrust equal to the condenser 115 dead weight, and means for transmitting to the engine supports all displacement forces 120 acting upon the condenser, other than that due to said condenser dead weight.

4. The combination, with an engine, having a downward extending exhaust conduit,

- and a condenser below the engine and having an exhaust inlet secured to the exhaust conduit of the engine, of means for constantly maintaining a uniform upward 5 thrust on the condenser substantially equal to the condenser dead weight and supports arranged to receive the resultant of all displacement forces acting on the condenser in excess of such upward thrust.
- 10 5. The combination, with an engine having a downward extending exhaust conduit, a movable bearing means, and a condenser mounted on said bearing means and provided with an exhaust inlet secured to the 15 exhaust conduit of the engine, of means for constantly maintaining a uniform upward thrust on said bearing means of such an amount as to transmit to the condenser an upward thrust substantially equal to the 20 condenser dead weight and supports arranged to receive the resultant of all displacement forces acting on the condenser in excess of the upward thrust maintained on said condenser.
- 25 6. The combination, with an engine having a downward-extending exhaust conduit, and a support for said engine, of a condenser arranged below and attached to said exhaust conduit, a stationary fulcrum device, 30 a lever fulcrumed on said fulcrum device, said lever being arranged to exert an upward pressure on the condenser, and means for applying a gravitational force to said lever to cause it to transmit continuously, to 35 the condenser, a substantially uniform upward pressure, the engine support being arranged to receive the resultant of all displacement forces acting on the condenser.
- 40 7. The combination, with an engine having a downward-extending exhaust conduit, and a condenser arranged below and rigidly attached to said exhaust conduit, of a series of stationary fulcrum devices, a series of 45 levers fulcrumed on said fulcrum devices, each lever being arranged to exert an upward pressure on the condenser, means for applying a gravitational force to said levers to cause them to transmit continuously, to the condenser, a substantially uniform upward pressure in opposition to the condenser dead weight, and a support for said engine, arranged to receive the resultant of all displacement forces acting on the condenser.
- 50 8. The combination with an engine, its supports and a condenser below said engine arranged to receive exhaust steam therefrom, of a support for said condenser con-
- sisting of a lever, a fulcrum support for said lever, a plurality of reducing levers associated with said lever on which the condenser is seated, stationary fulcrum supports for said reducing levers, means for connecting the ends of at least two of said reducing levers with one end of the first mentioned lever, and a counterweight on 60 said first mentioned lever arranged to normally exert an upward thrust on the condenser substantially equal to its dead weight, whereby the resultant of all displacement forces acting on the condenser in excess of 65 such upward thrust will be transmitted to the engine supports.
- 65 9. The combination with an engine, its supports and a condenser below said engine arranged to receive exhaust steam therefrom, of a support for said condenser consisting of a lever, a fulcrum support for said lever, a bearing plate on one end of said lever, a plurality of reducing levers on which the condenser is seated arranged to 70 co-operate with said bearing plate, stationary fulcrum supports for said reducing levers, and a counterweight on said first mentioned lever arranged to normally exert 75 an upward thrust on the condenser substantially equal to its dead weight, whereby the resultant of all displacement forces acting on the condenser in excess of such upward thrust will be transmitted to the engine supports.
- 80 90 10. The combination with an engine, its supports and a condenser below said engine arranged to receive exhaust steam therefrom, of a support for said condenser consisting of a lever, a fulcrum support for said lever, a bearing plate on one end of said lever, a plurality of reducing levers on which the condenser is seated arranged to co-operate with said bearing plate, stationary fulcrum supports for said reducing levers, adjustable bearing screws for the inner ends of the reducing levers arranged to contact with said bearing plate, and a counterweight on said first mentioned lever arranged to normally exert an upward thrust on the condenser substantially equal to its dead weight, whereby the resultant of all displacement forces acting on the condenser in excess of such upward thrust will be transmitted to the engine supports.
- 95 100 105 110 115 In testimony whereof, I have hereunto set my hand.

JOHN F. GRACE.
